UNITED STATES PATENT OFFICE

ALFRED MUSSO, OF EAST ORANGE, NEW JERSEY, ASSIGNOR OF ONE-HALF TO WILLIAM P. DEPPE, OF NEW YORK, N. Y.

RETORT FURNACE

Application filed March 20, 1929. Serial No. 348,379.

This invention relates to furnaces and processes practised in connection therewith.

One object of the invention is to provide a device of the character described, including 5 improved means for heating a chamber from the outside thereof.

Another object of the invention is to provide an improved device of the class specified including an exteriorly heated chamber, the 10 charge in which, at any point of the chamber, is subject to heating by conduction and radiation at substantially the same temperature, although the different points of the chamber may be at the same or at different 15 temperatures as predetermined.

Another object of the invention is the provision of a device of the nature set forth having improved means for movement through a furnace or retort chamber of the charge 20 that is being heat treated therein.

Another object of the invention is to furnish a device of the type mentioned having a heating chamber which is divided into a plurality of compartments by improved means 25 that restricts the flow of gases from one to another of the compartments and coacts for movement of the charge in the chamber through the successive compartments.

Another object of the invention is to construct 30 a device of the species alluded to, having a heating chamber through which is passed the charge that is being treated, which device includes improved means for separately removing from the chamber the gases in 35 different sections thereof.

Still another object of the invention is to provide a device of the character described having improved means to create a partial 40 vacuum in a retort and to exhaust all gases generated in the retort chamber in stages according to predetermined temperature or 45 temperatures.

Still a further object of the invention is the provision of a heating device operating under a co-ordinated temperature and pressure 45 gradients, and an improved control to automatically maintain the requisite temperature-pressure relationship.

Other objects of the invention are the provision of an improved device of the nature

set forth wherein a temperature gradient is maintained in an improved manner in the heating chamber; and wherein heat is imparted to the chamber without causing oxidation of the same; and wherein the gases generated are removed in one or more stages from the heating chamber without removal of the non-gaseous ingredients that are being treated regardless of how fine the same may be; and wherein an improved device controls and mixes the supply of air and gas. 55 60

Still further objects of the invention are to provide an improved process for heat treating a charge by conduction and radiation at opposite sides but at predetermined temperatures without contact with the products of combustion; also to provide an improved system of heating the charge by radiation under reduced pressure or partial vacuum. 65

Still further objects of the invention are 70 the provision of an improved process for the heat treatment of materials, wherein the factors of temperature, pressure, and reaction velocity are co-ordinated for equilibrium conditions; and an improved apparatus for 75 carrying out this process.

This invention is particularly intended for use in my process of low temperature reduction of metals, Serial No. 325,713, filed December 13th, 1928, and aims to provide an 80 efficient apparatus therefor.

It must be kept clearly in mind by those skilled in the art, that since the process, more specifically disclosed in copending process application, Serial No. 325,713, filed 85 December 13th, 1928, to which this apparatus is primarily directed includes a co-ordination of temperatures, pressures, and particular retort atmospheric conditions conducive to the chemical reactions involved, under the 90 limitations and physical forces necessary for the effective practice of the process, that the combinations of the structural features of the apparatus in their physical and functional relationships must also be co-ordinated in a 95 corresponding sense; hence the apparatus illustrated involves some unusual interrelations which have never been heretofore devised.

It must be particularly noted that the ap- 100

paratus suitable for this new process, illustrated in this disclosure employs for the first time, the principle of reducing iron ores with any kinds of coal in mass production conditions, in an air-tight retort, wherein is included the means for mechanically accelerating the substantially complete reduction of the materials being treated by means of solid carbon reduction. The gaseous reactions are substantially eliminated, through the continuous forcible exhaustion of all gases being liberated and formed in the process, at temperatures below the fusion points of material which eliminates melting, agglomeration, or sintering. The volatile constituents of coal and the maximum amount of CO available, continuously and forcibly withdrawn from the reducing ambient in this process, causes the novel result of the production of sufficient fuel gases to operate the system.

In this process, which is primarily devised for mass production conditions, particularly for the use of any kinds of iron ores, oxides, or carbonates, and any kinds of coal, in order to decrease the time for substantially complete reduction of the ores being treated, particularly iron ores, at lowered temperatures, it is essential to forcibly and continuously exhaust all gases in the retort as fast as formed, to practically eliminate the gaseous reaction conditions, and to maintain substantially solid carbon reaction, with chiefly CO produced, and little or no CO₂ produced, and with lower temperatures permissible in the retort, but high enough to cause substantially complete reduction, and yet not high enough to cause fusion, thus eliminating melting, agglomeration, or sintering in the materials being treated. For example, the maximum temperature for reducing iron ores mixed with coal, is approximately 950° C.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the several views.

In the drawings, which are submitted to show features of the invention, but not to limit the scope of the claims:

Figure 1 is a longitudinal view in vertical section of a device embodying the invention.

Fig. 2 is a cross sectional view taken on the line 2—2 of Fig. 1.

Fig. 3 is a similar view taken on line 3—3 of Fig. 1.

Fig. 4 is an enlarged fragmentary view of

the exhaust pipes and a strainer, shown in Fig. 1.

Fig. 5 is a view in section taken on line 5—5 of Fig. 4.

Fig. 6 is a vertical sectional view taken on line 6—6 of Fig. 1.

Fig. 7 is a view in elevation of a heating means for a retort with parts in section.

Figs. 8 and 9 are sectional views taken on horizontal and vertical lines, respectively, on Fig. 7.

Fig. 10 is a view in section of the fuel control and mixing apparatus.

Fig. 11 is a cross sectional view thereof taken on line 11—11 of Fig. 10.

Fig. 12 is a diagrammatic view of a co-ordinated temperature and pressure control.

Fig. 13 is a fragmentary view in vertical section taken on line 13—13 of Fig. 1.

Fig. 14 is a view in vertical section of a modified heating ring and furnace arrangement.

Fig. 15 is a view in vertical section of a still further modification of a heating ring.

Fig. 16 is a vertical sectional view taken on line 16—16 of Fig. 15.

Fig. 17 is a diagrammatic view of a modified arrangement of the heating rings with respect to the work or retort furnace.

Figs. 18 and 20 are fragmentary views in longitudinal vertical section of heating chambers with modified partition constructions.

Figs. 19 and 21 are transverse sectional views taken on the lines 19—19 and 21—21 of the devices shown in Figs. 18 and 20, respectively.

The advantages of the invention as here outlined are best realized when all of its features and instrumentalities are combined in one and the same structures, but, useful devices may be produced embodying less than the whole.

It will be obvious to those skilled in the art to which this invention appertains, upon becoming conversant with the features thereof, that the same may be incorporated in several different constructions. The accompanying drawings, therefore, are submitted merely as showing the preferred exemplification of the invention. The underlying scientific theory, as well as the objects of the invention will determine its scope, as it is possible to produce other devices which will accomplish substantially the objects of the invention.

The fundamental theory underlying this invention is that the velocity of a chemical reaction is a function of the ratio of the pressure to the temperature. By my improved process, this function governs the reaction throughout, so that the reaction velocities are uniformly accelerated or retarded, as the case may be. A reaction whose velocity is a

continuous function of the ratio of the pressure to the temperature, produces uniform results, without the formation of residual substances. The completeness of the reaction is assured in my improved process by the continuous removal of the gases, as well as by the pressure temperature ratio. Though, from a theoretical viewpoint, the increments of the rate of change of temperature and pressure ought to be infinitesimal, in actual practice this can be but approximated in stages as hereinafter indicated.

As a specific example of the subject matter set forth in the preceding paragraph, I may mention that in the process of mineral reduction, for instance, in that of ferric oxide (Fe_2O_3) by means of the fixed amorphous carbon of coal, we have two phases, viz., solid iron (Fe) and gaseous carbon monoxide (CO), coexistent at all times, while the carbon (C) and the oxygen (O) which form the CO are combining under equilibrium conditions. To better explain the fundamental theory, in the case of iron reduction, I will set forth the chemical equation of the reduction, which is:

This equation is to be considered as the effect 30 of the two simultaneous equilibria, viz.,

35 Of the two simultaneous equilibria, the first one tends to liberate the iron contained in combination with the oxygen in the ferric oxide, while the second equilibrium tends to eliminate the oxygen as such from the system by converting it to carbon monoxide. The 40 completion of the reaction, according to well established principles of physical chemistry, is brought about by the elimination of the gaseous phase CO from the system, by the exhaustion of the gases from the retort chamber as fast as they are generated. In order to further avoid the possibility of a reversible reaction, an excess of carbon is supplied and always present, conforming thus with 45 the well known principle of mobile equilibrium and the law of mass action. This brief discussion on the basic principles of my invention as applied to iron reduction, is general and applicable to all kinds of reversible 50 reactions which can be caused to occur in my apparatus. In all reactions, such as the reduction of iron above referred to, where gas is generated, and where the natural tendency would therefore be toward an increase of the 55 total pressure of the system, any reduction of the total pressure, will favor the reaction. On the other hand, there is for each pressure a corresponding definite temperature, and vice versa. This results in the theory that 60 in any system contemplated by my invention,

65 temperatures and pressures must be made to vary, in order to attain a completion of the equilibria involved, the course of the reaction is a function of the ratios of the pressure to the temperature. And this is the statement of the general process provided by my invention.

70 While for the reduction of iron ore, the temperature is increased and the pressure decreased, the invention is equally applicable to such reactions as require a decrease in temperature and simultaneous increase in pressure; or an increase or decrease of both temperature and pressure; or wherein one of 75 these factors remains constant while the other alone changes, although it is contemplated that the best conditions are obtained by causing both temperature and pressure to harmonize for the reaction: in each case, the 80 rate of the change of these factors, or the rate of change of the ratio of the factors is substantially constant, as, for instance, according to an arithmetic progression.

85 It is preferred that the temperatures and pressures herein be taken on the absolute scales, although other scales can also be used.

90 It is noted that, for certain reactions, successive changes of temperature and pressure may be such that the difference between the 95 ratios is substantially zero.

95 Referring again to the reduction of iron, the increase of temperature and decrease of pressure tends to promote the dissociation of the iron oxide. The decrease of pressure, however, militates against the formation of the carbon monoxide, but this is counteracted by several factors, among which are the increase of temperature, the natural affinity of oxygen for carbon, and the presence of 100 hydrogen which acts as a catalyst in the formation of carbon monoxide. In the last stages of the reduction, hydrogen is evolved in rather considerable quantities from the carbonaceous fuel which is used in the charge 105 and acts effectively as above stated.

110 The term "charge" is intended to denote the ingredients in the retort at any stage of the reaction, or any materials or articles that may be advantageously heat treated in a furnace embodying one or more features of this invention, regardless of whether or not such heat treatment is accompanied by a chemical reaction.

115 Generally described, the invention provides an elongated heating chamber, which may be in the nature of a cylindrical retort. The same is rotatable about its axis, which is preferably inclined with the horizontal, to cause the charge introduced in the retort to move therethrough. The end portions of the retort are each formed with a concentric series of conveyer pockets which rotates with the retort. Coacting with each series of 120 pockets is a circular stationary closure mem- 125

ber so arranged to permit a lowermost pocket to receive a portion of the charge, but to close the filled pocket as it moves upward, and finally to permit the charge to be removed through an opening in the member with which the pocket comes into registry, when the same reaches its uppermost position. The charge in the pockets thus acts as a seal and contributes to render the retort air tight. This system of conveyer pockets feeds the charge to be treated into the retort at the upper end of the retort and feeds said charge from the retort after treatment at the lower end of the same. Dividing the retort into a plurality of successive compartments are transverse partitions which are of substantially gas tight construction. These partitions comprise the conveyer features that are provided at the ends of the retort, and thus cause the charge to be passed from one compartment to another. Extending centrally through the retort is a stationary shaft that supports the stationary circular members of the partition conveyer construction. Associated with the shaft are a plurality of pipes communicating individually with the compartments, whereby the gases in the latter may be exhausted by pumps. A screen may serve to prevent finely divided ingredients in the retort from entering the pipes. A scraping blade or other similar device may keep the strainer clean. The retort is heated by radiation from the outside by means that are disposed between the retort and the wall of the furnace, the intraspace being closed so that air may not leak thereinto. Preferably the said means are in the nature of stationary rings concentric with the rotating retort and disposed therealong in spaced relation to each other; thus transverse sections of the retort are maintained at the same temperature along the peripheral surface of each section, so that the charge lying along the bottom of the retort is uniformly heated from its underside by conduction and from above by radiation, the latter occurring with high efficiency due to the exhaustion of the gases from the retort, and the consequent elimination of any gas film that would otherwise adhere to the interior surface of the retort wall. The said rings may consist of pieces of refractory material calcined with a suitable binder and having considerable voids to permit passage therethrough of the waste combustion gases, while the outside of each ring is glazed to render the same gas tight. Premixed gas and air in combining ratio are fed under pressure into each ring, and surface combustion occurs therein. To maintain a temperature gradient, the spacing of the rings may be varied. An automatic control co-ordinates the temperature and pressure in the retort in order to obtain the proper ratio at any time or in any part of the retort.

For metallic reduction, an apparatus as above described is preferably employed, but for oil shales or similar materials, the retort may be maintained at constant temperature throughout the length thereof, and the subdivision of the retort into compartments with separate exhaustion of the same may be eliminated.

While the invention contemplates preferably the application of the same to the reduction of minerals, certain principles thereof are applicable to furnaces of heating chambers of widely different types where uniform heating is desired, with or without the use of a retort, as, for example, in soaking furnaces; and also to different chemical or mechanical operations, as, for instance, roasting or driving off volatile constituents in materials other than mentioned, or treating substances under varying conditions of temperature and pressure whether the latter be partial vacuum or high pressure.

When applied to the reduction of minerals according to my improved process above mentioned, the volatile gases generated may be consumed to heat the retort. Where oil is a product, the same may be partially gasified and burned according to the method of surface combustion. To heat the retort, hot products of combustion from any suitable source may be circulated about the same, and the heat so obtained may be generated in a central heating chamber and directly passed about the retort or through tubular devices capable of radiating their heat upon the retort. Electrical heating can be employed also, although this may be considered as too expensive for ordinary commercial use. It suffices that a uniform temperature is obtained for the charge that is being treated, both by conduction and radiation, and especially when accompanied by a simultaneous rotation of the retort.

The end walls, or partitions, or both may assume different forms, depending, among other factors, upon the partial vacuum that is desired in the retort, and whether a pressure gradient is maintained in the same, or whether the gases are exhausted in separate compartments or stages but at substantially the same pressure.

In the treatment of finely divided materials of any kind, as, for example, in the reduction of a mineral by a solid fuel, there is a known interstitial volume V_1 , and a known free volume V_2 in the retort, the ratio of the volumes being

$$\frac{V_2}{V_1} = m,$$

a number larger than 1. Now, considering at any instant the pressure and temperature, and P_1 being the pressure in the interstices,

and P_2 the pressure in the heating chamber,

$$\frac{P_1 V_1}{T} = \frac{P_2 V_2}{T};$$

5 and because

$$V_2 = m V_1, P_1 = m P_2; \text{ or } P_2 = \frac{P_1}{m},$$

10 which may be even less than one atmosphere. In all cases, the value of P_2 is less than if no exhaustion occurred, for then P_2 would equal P_1 , that is, the pressure in the free space in the retort would equal the pressure in the 15 interstices. Since

$$\frac{V_1}{V_2}$$

is known

$$\frac{P_2}{P_1}$$

20 can be maintained constant, for each condition of temperature in the retort. The electro-
25 thermal mechanical device disclosed herein renders it possible to automatically maintain the pressure-temperature ratio. Similarly, because the ratio of the volumes V_1 and V_2 is known or can be predetermined for any re-
30 quired pressure ratio the temperature to correspond to the initial required conditions can be readily obtained. Thus for any given conditions, and since the ratio of the volumes V_1 and V_2 is substantially constant through-
35 out the retort, it is always possible to determine the ratio of the pressure P_2 of the retort chamber to the temperature T of the same. From the preceding discussion, the value of the ratio P_2/T is obviously a function of the 40 initial condition and therefore can be predetermined or modified as one of the two terms of said ratio may vary in the course of the reaction.

45 The rate at which the ingredients that are being treated undergo the desired change, and more particularly the reaction velocity, as in reduction of a mineral, is fixed by the pressure-temperature ratio, which thus pre-determines the time that is required for the 50 complete reduction of the mineral. Accord-
ingly, the time during which the ingredients are to remain in the retort, and consequently the proper rotational speed of the retort may be ascertained. By thus co-ordinating tem-
55 perature, pressure, and reaction velocity to assure proper equilibria at various points of the reactions, there results continuous performance with completeness of the reactions and purity of the metal. With the elimina-
60 tion of secondary reactions, by the rapid removal of gases from the retort, the reduction of the mineral is rendered entirely smooth, and free of even those interruptions or ob-
65 stacles that would otherwise cumulatively

prevent the completion of the reduction and the obtaining of a pure metal.

Referring in detail to the drawings, 20 denotes a device embodying the invention. The same constitutes an improvement over my 70 co-pending application for patent on retort furnace, Serial No. 259,406, filed March 6th, 1928. The said device comprises a heating chamber or retort 21, made of any suitable material consistent with the temperature required. For the comparatively low temperatures used in my process, the retort may be made of steel with an inside and outside coating of chromium. For higher temperatures a chrome alloy steel may be found suitable. 80 In general, any metallic alloy adapted to withstand high temperatures is employed, the use of metal permitting a more economical transfer of heat through the wall of the retort and also a lighter construction in the 85 mounting thereof.

The retort 21 may be of cylindrical or other form rotatable about its axis which makes an angle with the horizontal to move the charge therein from the upper inlet end 22 90 to the lower outlet end 23 thereof. The retort may also be differently arranged, particularly if a different system is employed for moving the charge through the rotor.

The retort is mounted in a furnace 24 hav-
ing an elongated chamber 25 to receive the same, which chamber is closed by stationary 100 end plates 26, 27. The wall of the furnace may be constructed of refractory brick or other like material and the end plates may be of metal of a heat resisting nature, prop-
erly insulated.

The end portions of the retort are en-
larged in diameter at 28, 29, and the free 105 edges of the same are received in annular re-
cesses 30 in the end plates to form a tight connection. The member 29 includes an op-
positely projecting annular flange 31 that 110 engages in a circular recess 32 in the furnace wall.

Carried exteriorly by the member 29 is a gear 33, whereby the retort may be rotated at a predetermined speed by any suitable source of power, such as an electric motor. Suitable idlers, in the nature of pinions, 115 whose teeth mesh with those of the gear 33, may serve to support the retort, but this ar-
rangement being readily understood, has not been shown. At the other end of the retort, a circular band or rail 34 takes about the same, and rides on idlers 35 to support the retort. Similar band and idlers are pro-
vided at the center of the retort. To obtain 120 access to the idlers, heat insulated plugs 35a may be used.

The circular spaces within the members 28, 29 are divided by radial walls 35 into a plu-
rality of aligned circular series of pockets 37, 38, which constitute conveyers. The radial 130 walls terminate at 39 so as to extend in the

general direction of the length of the retort and also radially inward so as to terminate at 40 in spaced relation to the axis thereof. At 39, however, the conveyer pockets are 5 closed by the stationary end plates 26, 27 with which the radial bucket partitions 36 have clearance. Closing all except the uppermost and lowermost pockets of the conveyers 37, 38 at their inner edges 40 are circular 10 or substantially cylindrical drums or closure members 41, 42, respectively, the same being fastened to or integral with the end plates and are substantially equal in diameter and coaxial with the retort, but fixed with 15 respect thereto, being mounted upon a stationary shaft 43 that extends centrally through the retort and is secured at its ends in the hubs 44 of the said end plates. Each of the members or drums 41, 42 has a sup- 20 porting disk portion 45 through which the shaft passes. At its upper part, the member 41 has an opening 46 communicating with a downwardly inclined chute 47 passing through the end plate 26, with the lower wall 25 of the chute extending to the disk 45 to which it may be secured. The lower part of the member 41 has an opening 48 in the wall 45 thereof, there being a top entrance member 49 for said opening extending into 30 proximity or fastened to the end plate 26. The charge in the retort will tend to load through the opening 48 into any lowermost pocket of the conveyer 37 and be carried upward with the rotation of the retort, about 35 the circular closure member 41 until the pocket comes into registry with the opening 46 permitting the load therein to be discharged from the pocket into the chute 47. The member 42 at the inlet end of the retort has openings 50, 51 similar to those at 48 and 46, respectively, so that charge may be carried from a hopper 52 down a chute 53 and thence through the opening 51 into any lowermost pocket of the conveyer 38, after which the 40 charge is carried upward in the pocket about the member 42 and finally discharged through the opening 50 down an incline 54 into the retort. 45

The heating chamber or retort 21, is divided into a series of consecutive compartments 56 to 59 by a plurality of transverse walls or partitions 55 comprising conveyers according to the principle of the conveyers 37 and 38. Each of the said partitions includes 50 a ring plate 60 secured to the wall of the retort and having a circular series of radially extending blades 61 that have free edges 63 and 64, the former projecting toward the axis of the retort, and the latter toward the 55 inlet end thereof. The said blades provide a circular series of conveyer pockets 55a concentric with the retort. Closing the said conveyer pocket at the edges 63, 64 thereof are circular closure members 65, each of which 60 includes a disk 66 mounted on the stationary 65

shaft 43 and coacting with the edges 64. Each of said disks carries a cylindrical drum 67 having closure coaction with the edges 63. At the upper part of the drum, the same has an opening 68 to register with an adjacent conveyer pocket. Now each disk has an inlet opening 69 disposed to one side of the vertical plane of the retort, according to the counter-clockwise direction of rotation of the same, which will cause the charge in the retort to pile toward the right side thereof. If the retort should move clockwise, the inlet 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

Thus at the inlet and outlet of the retort, and at the partition 55, positive movement of the charge is assured, under conditions that substantially prevent leakage of air, or gas, or both. The finely divided ingredients of the charge serve to seal the clearance spaces at the conveyers. Within the retort the charge may thus be caused to move at a positive uniform speed through the successive compartments 56 to 59, depending upon the speed of rotation of the retort and the consequent speed of the conveyers.

To obtain further air tightness of the retort, the chutes 47 and 53 may be each provided with a plurality of spaced fly valves 71, 72 which are geared together in any suitable manner for simultaneous movement. The valves are set so that when one of them is open, the other is closed, thus avoiding air leakage. The quantity of charge passing through a chute at any operation of the valves is determined by the space between the valves. Since the charge is in finely divided condition, practically no air will enter therewith.

Extending along the stationary shaft 43, are a plurality of pipes 73 to 76 which enter the retort at the inlet side thereof, and each of which communicates with one of the compartments 56 to 59 respectively. The shaft 43 may be grooved longitudinally as at 77 to receive the pipes, thus making for a highly compact construction. At the retort partitions 55, sleeves 78 are provided closely receiving the said pipes and having flanges 79 at the ends of the sleeves, which may extend to the surface of the said pipes and of the shaft. The drums 65 are securely mounted on the collars, the flanges of which are on opposite sides of the drums.

Externally of the retort, the pipes communicate individually with exhaust pumps 80 to 83, that are of any suitable type or size according to the reduction of pressure desired in the retort and in the particular com-

parts thereof. By means of this arrangement, a pressure gradient can be maintained in the retort, with pressures which may be considerably below atmospheric, varying from one to another of the successive compartments 56 to 59.

To prevent finely divided ingredients of the charge in the retort from being drawn into an exhaust pipe, any suitable means well known in the art may be employed, whether electrical or mechanical, to remove them, as by centrifugal action, or simple screens 84 may be used. These are cylindrical in form to surround the pipes and extend from end to end of each compartment. They may be secured to any suitable means, as, for example, the flanges 79, and similar flanges 85 adjacent to the end walls of the retort. Thus the gases exhausted by the said pipes are thoroughly screened. Due to the large screen area, there is practically no clogging of the screens. Furthermore, the screens are positioned remotely from the charge in the bottom of the retort, and may, in an obvious manner, be disposed in the upper or other part of the retort, and function equally well with the pipes in the central position thereof. The several screens may be of varying fineness to suit the compartments, and a plurality of screens may be disposed exteriorly of each other with the screen of larger mesh outside. If desired, a scraper may coact to automatically clean the screens coincident with the rotation of the retort. If desired any suitable design of dust traps or tar trays, or scrubbers may be included in the line between the retort and the pumps, exhausting the gases as fast as formed.

To brace the shaft 43 and the said exhaust pipes, a plurality of arms 87 extend from the wall of the retort and terminate in a hub 88 with which the collars 78 have rotatable relation.

To heat the retort, a plurality of spaced heating zones 90 are provided in the furnace chamber, extending circularly about the retort. Heat may be supplied to the zones in any suitable manner, by the combustion of fuel, or electrically. These zones are in the form of spaced cylindrical areas or rings, the width whereof, and the spacing may vary to maintain any desired temperature gradient. However, regardless of the specific form or nature of the said zones, the same comprise radiant refractory areas that heat the retort by radiation. These areas are designed to be particularly adapted for uniform radiation of heat, whether the heat be supplied thereto externally or internally. More specifically, they provide a means of indirect heating of the retort by internally fired devices outside of the retort, which, on becoming hot, provide large masses of radiating refractory body, and none of the gases of combustion need come in contact with the wall of the re-

tort. The wall of the retort is spaced from these areas any suitable distance consistent with economical heating under uniform radiation to the retort, and while this space as shown in the drawings, is preferably comparatively close, it may be substantially increased to meet all operating conditions. Since the radiating zones are of ring form as above stated, any compartment or transverse section of a compartment is subject to uniform temperature all around to impart uniform heating by conduction and radiation to the charge in the retort. Since the retort is exhausted causing the rapid removal of inert gases from along the wall of the retort, the radiation of heat on the charge is improved.

Each zone 90 may include a ring 91 that is set into the wall of the furnace or extends into the chamber 25 thereof as shown. The rings may all be of the same construction, being made of a porous mass of refractory which is gas tight along the outside thereof. Thus a refractory consisting of pieces 92 of carborundum, zircon, or graphite may be used enclosed in a gas tight refractory wall. Preferably, the said pieces have been previously mixed with a binder, as for instance, tar, then moulded into ring form, and calcined at a temperature above that to which the ring will be subjected to volatilize all hydrocarbons of the binder and leave a strong porous body of refractory. Then the voids at the surfaces of the ring can be filled with refractory to provide a comparatively smooth base. Finally, the outside surfaces of the ring are glazed at the base thus formed to provide a gas tight surface, but the surface 93 of the ring that contacts the furnace wall may be glazed or permitted to remain unglazed and sealed with the furnace wall. The latter is preferably also glazed to render it impervious to gases. The glazing material is any high temperature siliceous material having a low coefficient of expansion, and can be carried out in a manner well known in the art.

The lower part of the refractory ring 93 is open to provide a recess 95 having opposite surfaces 96 communicating with the burner nozzles 97. The latter discharge premixed gas and air in correct combining ratio through the opposite portions 92a of the said ring. The said orifices may constitute parts of a single burner 98. To seal the burner with the refractory ring, a strong high temperature cement 99 may be used, supported on a block 100 which rests on a plate 101. The cement 99 is intended to reinforce the ring at the region where the maximum temperatures may be obtained therein. It will be appreciated that the rings constitute structural shapes that can be efficiently supported by the furnace wall over a large area of the rings.

To protect the orifices 97 against overheating, they may discharge into conical spaces 102. These spaces serve to convey the gases at high velocity to the surfaces 96. The 5 ring adjacent to the said surfaces may be thickened as shown at 103 to provide sufficient interstitial area at the surfaces mentioned for rapidly receiving the gases without excessive resistance. An upper portion 104 of the ring is unglazed to provide an opening 10 for the escape of the burnt gases.

The fuel is consumed in the interstices of the pieces of refractory 92, with flameless or surface combustion, the principles whereof 15 are well known. It is intended that the mass of the refractory rings be sufficiently great in proportion to the fuel consumed, that, after the furnace has been thoroughly heat soaked and at equilibrium, the temperature 20 thereof be substantially uniform. It will be evident to those skilled in the art, that the said refractory rings can, if necessary, be modified to suit different operating conditions, and yet cause the temperature thereof at 25 the lower portion of the retort to be substantially equal to that at the upper part thereof, regardless of whether this result be accomplished by providing a solid thick wall along the said ring adjacent to the wall of the retort, or providing a wall of this type of varying 30 thickness.

With reference to surface combustion, it will suffice to briefly state that the gaseous fuel is completely consumed with little or no 35 excess oxygen. When the charge of gas and air is ignited in contact with the surface of the refractory material, the heat developed is so intense that the refractory becomes rapidly incandescent. Due to radiation of heat from 40 one piece of refractory to another, the entire mass of the porous refractory body becomes ultimately incandescent, so that the entire ring becomes an efficient radiating medium. The glowing refractory material acts as a 45 catalyst and causes an almost instantaneous combustion. The waste gases pass out through the interstices of the refractory material at any suitable point in the ring, and are utilized in heating the low temperature 50 end of the retort.

The fuel and air may be supplied to the burner 98 in any suitable manner, as, for instance, from a mixing chamber 105 receiving 55 fuel gas and air through separate pipes 106 and 107 respectively communicating with headers 108 and 109. From the mixing chamber, the gases flow through a tube 110 into a control or regulating chamber 111. The latter may be cylindrical in form, and has rotatably fitted therein a hollow valve 112 having 60 an opening 113 to communicate with the tube 110. Connected in any suitable manner to the valve 112 is a coaxial Venturi tube 114 to pass the mixture of gases into the burner 98. Extending from the said valve is a spin-

dle 112a packed at 112b and carrying an arm or pulley 112c. Thus a belt connection may serve to regulate from a central point all of the said valves for the different combustion zones. Each valve may be set at any desired predetermined position with respect to the other valves, and each pulley may be of a different size so that the rate of opening or closing of the valves may be varied as among themselves. 70

After leaving the refractory rings, the gaseous products of combustion enter the openings 115 in the top wall of the furnace. These openings are positioned between adjacent refractory rings, and communicate with a by pass 116 in the said wall. This by pass permits the products of combustion to pass to the inlet end portion of the retort where they are circulated spirally about the retort, since this portion of the furnace is not provided with the refractory rings. Thus a temperature gradient is obtained which is desirable in the reduction of minerals. The spiral travel of the gases may be obtained by placing spaced segmental plates 117 and 118 at the 80 top and bottom of the furnace chamber between the wall thereof and the retort. To prevent short circuiting of the gases from the refractory rings to the spiral passages 119, the retort has a plurality of annular ribs or flanges 120 extending into corresponding recesses 121 in the furnace wall; and a similar flange 122 is provided at the inlet end of the retort to guard against leakage of air into the furnace chamber and prevent oxidation 90 of the retort. From the spiral passages, the products of combustion enter an outlet 123.

To automatically regulate the temperatures and pressures in the retort, a central control 125 is provided. This includes thermocouples 126 and 127, the former of which may extend into the compartment 59 of the retort, through the end plate 26, while the latter may be disposed externally of the retort in proximity to the same compartment. 100 A third thermocouple 128 is positioned outside of the retort adjacent to the wall of the retort compartment 57. Each of the thermocouples may be connected to suitable induction coil and magnets 129, 130, and 131a, 110 respectively. The latter operate a control means, as, for example, the corresponding valves 112 by any suitable means including levers 131 connected to the pulleys 116. Induction coils and magnets 132 to 135 are provided to control throttle valves 136 to 139 of the primer movers or vacuum pumps connected to pipes 73 to 76 respectively. The devices 132 to 135 coact with the devices 129 to 131a to maintain the desired temperature pressure relation. One form of the coaction, 115 comprises a circuit 140, 141 with which the devices 132 to 135 are connected in parallel. The devices 129 to 131a may be in series with the circuit 140, 141 by means of wires 142, 120 130

and rheostats 143 may be provided for the devices 129 to 131a. Power lines 144 supply electricity to the several devices. The rheostats are operated by the induction magnets, and the relation of the two is such that the temperature pressure ratio may be kept constant, though one of these factors should accidentally change.

In Fig. 14 is shown a modification of the invention, wherein the rings are arranged to discharge the waste gases at a point where the temperature of the gases has dropped sufficiently to be incapable of imparting heat to the ring. Thus the ring 91a has openings 5 or is unglazed at 91b intermediate of the upper and lower ends of the ring. The waste gases that leave the rings at 91b enter recesses or passages 24a in the wall of the furnace 24 and flow upward exteriorly of the 15 rings into the outlet 116. The said passages 24a may be closed by the rings themselves, and the waste gases will directly heat the upper side portions 24b of the furnace, reducing the loss of heat by conduction through the 20 furnace walls, and affording a high degree of uniformity in the heating of the retort 21.

In Figs. 15 and 16 is shown a modified arrangement of the rings 91. This embodiment 145 is disposed circularly about the 30 heating chamber or retort 21, which it heats primarily by radiation, as above described, and may be similarly mounted within a furnace such as 24. It includes a tubular refractory member 146, that has been suitably 35 moulded and baked. The lower portion of the said member is enlarged to constitute an enclosure 147 which is analogous to a combustion chamber. The upper portion of the member is in the nature of a ring 148 that 40 conducts the hot products of combustion from the chamber 147 around the retort to discharge the same through an opening 149, whence they flow through passages 115 into the by pass 116 as hereinbefore described. 45 The chamber 147 is open at its bottom at 150 to receive a hollow tile 151. The latter may be open at the bottom, but its upper closed end 152 is spaced from the inner wall 153 of the tubular member. Positioned in the 50 said tile 151 is a burner 154, having a plurality of oppositely extending heads 155 lying in a plane at right angles to the axis of the tubular member 145. Each of the heads has a plurality of small orifices to discharge 55 the premixed air and fuel through openings 156 in the coacting opposite walls of the tile. To protect the burner, refractory blocks 157, 158 are disposed thereabout, which also centrally position the same. Supporting the 60 tile and also closing the bottom of the tubular member 145 is a refractory member 159 which rests upon a plate 159a. Preferably completely filling the tubular member 145 is a porous refractory material 160 that encloses the tile 151. This material may be in

the nature of pieces of broken refractory upon which the gas and air mixture enter after passing through the openings 156 in the tile to burn with surface combustion. The sizes of the pieces of refractory 160 is predetermined to permit the required speed of travel of the products of combustion through the same with a view to equalizing as far as possible the temperature within the tubular member 145. As one possible arrangement, 70 it may be suggested that the space 161 immediately about the tile 151 may be packed with small pieces of broken refractory for localized intense surface combustion; then large pieces of refractory are used to fill the 80 rest of the tubular member, and provide sufficient interstitial volume not to cause undue frictional resistance to the flow of the gases. Should the inner wall 153 be somewhat thick, it may be perforated as shown 85 at 163 to provide openings through which the incandescent refractory 160 may directly radiate upon the retort. These radiant heat openings may also vary in size to afford uniform heating of the retort. It is noted that 90 the bottom portion 164 of the inner wall 153 is imperforate to guard against any possibility of undue transmission of heat to the retort at this point. That a portion of the products of combustion may be in direct contact 95 with the retort may be of lesser importance since the material of the latter is well adapted to resist the action thereof. As the radiant heat acts between adjacent pieces of refractory in the ring, these pieces will all become incandescent ultimately, and thus afford the main source of heat for the retort. 100 To ignite the fuel, removable plugs 164a may be provided, accessible at the bottom of the furnace 24. 105

In Fig. 17 is shown a modified arrangement of the heating rings, which can be practised with either form of ring hereinbefore described, and now denoted as 165. These rings 165 are disposed along planes forming an acute angle with the retort, so that the effective heating zone of each ring is defined by its projected area 166. As the retort rotates a high degree of uniformity of heating 110 may be obtained. The said rings may be arranged to space the projected areas, or the angle of inclination or widths of the rings 115 may be varied for the successive rings, to obtain a temperature gradient.

In Figs. 18 and 19 is shown a modified arrangement of a partition or wall 167 for a rotary retort 168. The latter may consist of a plurality of sections 169 having any suitable interengagement at 170, as, for example, by means of an annular flange 171 snugly receiving an end 172 of an adjacent section. At the joint 170, a groove 173 is provided to slidingly receive the edge of a disk 174 which is stationary on the collar 78, and accords a substantially gas tight connection. In the 130

lower portion of the disc, the same is provided with an opening or passage 175 laterally positioned according to the surface 176 of the charge in the retort, that seals the said 5 passage through which the charge passes due to the slope of the retort. In making the passage 175, an arcuate flange 177 may be formed to fill that portion of the groove adjacent to said passage.

12 In Figs. 20 and 21 is shown a further modification of the invention which includes a partition or wall 178 and having a passage 179 for the movement of charge that seals the same. A slight clearance may be observed 15 at 180 between the edge of the partition and the wall of the retort.

It will be appreciated that the partitions 55 are adapted for a variable charge in the retort, while those shown at 167 and 178 require a definite minimum charge to seal the 20 passages therein. Furthermore, the partitions 55 are adapted for a positive movement of the charge at any predetermined speed.

In conclusion, it is desired to point out that 25 considerable space has been devoted herein to the exposition of various embodiments of the invention, in order to obtain a clear, full, and operative disclosure; but it is not desired to convey the impression that the means shown are substantially the only ones that 30 can be used. Thus while heating members of ring form have been shown, circular heating zones can be created in the furnace by other means, or burners well known in the 35 art. Further, the retort, the conveying means for the charge, and the partitions can all be changed, separately, and collectively, within the scope of the broad invention.

I claim:

40 1. An apparatus of the character described, including a chamber through which the charge therein is adapted to move, means to heat the chamber, means to divide the chamber into a plurality of compartments to prevent the flow of gases from one to another of 45 said compartments and to cause the charge to move through the successive compartments, and positive means for forcibly exhausting the gases from the retort compartments.

50 2. A device of the character described, including a rotary heating chamber, and relatively stationary means therein dividing the same into a plurality of compartments and preventing a free flow of gases from one to another of the same, said chamber making an angle with the horizontal to cause the charge to move therealong, said means having a restricted opening through which the charge passes in its movement aforesaid, and an annular series of pockets rotating with the chamber, the pockets successively communicating with said opening in relatively close relation thereto.

55 3. A device of the character described, in-

cluding a rotary heating chamber having a charge on the lower wall thereof, said chamber having means therein below its axis of rotation to receive a part of the charge, said means coacting with the chamber to move therewith on rotation of the latter to a position above the said axis, and means coacting with the first mentioned means for sealing the charge therein and causing the same to be discharged back onto the lower wall at a 70 point relatively in advance of that at which the charge was received.

4. A device of the character described, including a retort, means to divide the same into a plurality of compartments and restrict the flow of gases between the compartments, and means to receive and enclose successive batches of the charge to cause the same to move from one to another of the compartments past the first mentioned means. 75

5. A device of the character described, including a retort divided into a plurality of compartments through which the charge is successively movable, means separately exhausting the gases from the compartments, 90 and means heating the compartments to different temperatures.

6. A device of the character described, including a plurality of compartments through which a charge is successively movable, means to heat the compartments at temperatures that increase from the first compartment to receive the charge, to the last compartment, and means to exhaust from the compartments the gases therein. 95

7. A device of the character described, including a retort divided into a plurality of compartments through which the charge is successively movable, means separately exhausting the gases from the compartments, 100 means heating the compartments to different temperatures, and means preventing the removal of finely divided material from the compartments with the exhausted gases.

8. A device of the character described, including a rotatable retort, means therein dividing the same into a plurality of successive compartments, said means including a stationary member having an opening through which the charge in the retort moves 110 from one to another of the compartments, and central means extending through said retort and said member to support the same, said central means having tubular means associated therewith to separately remove the 115 gases from the different compartments.

9. A device of the character described, including a heating chamber having a plurality of compartments, means for moving the charge through the successive compartments, means to heat the compartments to different temperatures, and means to separately remove from the compartments the gases therein. 120

10. A device of the character described, in- 125

- cluding a heating chamber having a plurality of compartments, means for successively moving a charge through the compartments, said means coacting with the chamber to seal the compartments in substantially gas tight relation from one another, means to heat the compartments to different temperatures, and means to separately remove the gases from the compartments. 5
- 10 11. A device of the character described, including heating means having a plurality of compartments coacting for the movement of the charge through said compartments, and means for maintaining different gas pressures in the different compartments. 15
12. A device of the character described, including a retort having a plurality of compartments, said retort having means for moving the charge successively through the compartments, and means for the separate removal of the gases in the compartments. 20
13. A device of the character described, including a plurality of closed compartments, means for moving a charge through said compartments, heating means and gas exhausting means for said compartments, separate control means for the heating and exhausting means, and a unitary means for automatically regulating both control means. 25
- 30 14. A device of the character described, including a plurality of compartments, means for moving a charge through the compartments, means to heat the compartments according to a temperature gradient for the compartments that increases in the direction of movement of the charge, and means to maintain a pressure gradient for the compartments that decreases in the direction of movement of the charge. 35
- 40 15. A device of the character described, including a heating chamber, means to vary the temperature therein, means to vary the gas pressure therein, and unitary means to automatically regulate the first and second mentioned means. 45
16. A device of the character described, including a closed heating chamber, and means for controlling the temperature therein, means for exhausting the gases therefrom, means for controlling the exhausting means, and other means for simultaneously operating both controlling means so that an increase in temperature is accompanied by a decrease in pressure. 50
- 55 17. A device for the reduction of pulverized ores, mixed with coal, including a retort, means for heating the retort from the outside, means for causing a charge to be continuously fed through the retort, and means for forcibly exhausting from the retort the gases therein, the exhausting means including separate tubular elements communicating with different parts of the retort for separately withdrawing the gases from the 60 zones in which they are generated. 65
18. A device for the reduction of pulverized ores, including a closed retort, means for heating the same from the outside, the retort having means for continuously feeding a charge therethrough, means for forcibly continuously exhausting the gases in the retort and to produce a decreased pressure therein, and means coacting with the exhausting means to prevent the removal of finely divided solid materials with the exhausted gases. 70
19. A device for the reduction of ores including a retort, the same having means for continuously feeding a charge therethrough, means for externally heating the retort according to a temperature gradient, and means for forcibly separately withdrawing the gases in the retort from the different respective zones therein in which the gases are generated. 75
- 80 20. A device including an elongated retort, and means for heating the same from the outside, said means including a plurality of thin walled, internally fired elements extending around the retort for radiating heat thereon, said elements being of varying width with respect to each other for maintaining a temperature gradient in the retort. 85
